UNITED STATES PATENT OFFICE.

PLINY W. SMITH, OF ROCHESTER, NEW YORK.

DEVELOPING TANK.

1,424,423.

Specification of Letters Patent.

Patented Aug. 1, 1922.

Application filed June 20, 1921. Serial No. 478,917.

To all whom it may concern:

Be it known that I, PLINY W. SMITH, a citizen of the United States, residing at Rochester, in the county of Monroe and State of New York, have invented certain new and useful Improvements in Developing Tanks, of which the following is a specification.

The object of this invention is to provide a new and improved form of developing tank for developing photographic negatives, more especially dental X-ray films in which the tank uses a minimum amount of developer and is intended to be used in a bath of cold water to reduce the temperature of the developer.

This and other objects of the invention will be fully illustrated in the drawing, described in the specification and pointed out 20 in the claims at the end thereof.

In the drawings:

Figure 1 is a perspective view of the developing tank and rocker.

Figure 2 is a vertical transverse section 25 through the tank.

Figure 3 is a modified form of the tank showing a receptacle in which can be set the rocker, being a part of the receptacle.

Figure 4 is a perspective view of the receptacle alone slightly modified from the form of the receptacle shown in Figure 3.

Figure 5 is a perspective view of the developing tank with still another modification of the receptacle and the mount and 35 rocker for the developing tank.

Figure 6 is a view of another form of the developing tank with a detachable rocker therefor.

In the several figures of the drawing like 40 reference numerals indicate like parts.

In the drawings, reference numeral 1 indicates a tank which is preferably made long and high and narrow and is open on the top 2 and is closed on the other five sides. Fas- 45 tened to the bottom of this tank at the middle thereof and extending transversely thereto is a round bar 3 which serves as a rocker for the tank and also serves to hold the tank in an upright position, that is, it 50 prevents the tank from tipping over side- wise, and acts as a weight which contributes to holding the tank down when it is im- mersed in a receptacle of cold water. The 55 length of the bar 3 is several times the width of the tank to which it is attached so as to

give the tank corresponding stability in holding it in its upright position.

In use, the tank is put into a receptacle of any convenient size which receptacle contains cold water which lowers the temperature of the tank and the developer that is contained therein. The developer is put into the tank and the film to be developed is immersed in the developer and the tank is rocked back and forth on the rocker 3. The cold water cools the developer and secures the development of the film under the best conditions and the shape and size of the tank secures the development with the least amount of developing fluid. After the development is completed the film is removed and fixed in the usual way, and the tank can be emptied of the developer and cleaned.

In Figure 3 I have shown the developing tank without the rocker, the rocker 4 in this case being made a permanent part of the receptacle 5 which receptacle is also provided with the bars 6, 7, 8 and 9 which run the length thereof and are fastened in the ends thereof and are spaced far enough apart to receive the developing tank 1 with suitable clearance. The developer is put in the tank 1 and the cool water in the surrounding tank 5. The tank 1 can then be rocked back and forth on the stationary 85 rocker 4. In Figure 4 I have shown the same kind of a tank in which is provided the U shaped bars 10, 11, 12 and 13 which are fastened in the sides of the tank with clearance enough between them to receive the developing tank.

In Figure 5 I have shown a similar tank 5 in which the wire cradle 15 is supported bent from a single piece of wire having a rocker 16 at the bottom and having side rails with 95 clearance enough between them to receive the development tank and permit the rocking thereof while the cradle remains stationary.

In Figure 6 I have shown a developing tank 1 with a wire cradle 20 detachable 100 therefrom which cradle has a rocker 21 at the bottom thereof on which the tank and rocker rests permitting the rocking of the tank and cradle.

I claim:

1. A relatively long and narrow developing tank having a rectangular bottom, a rocker attached to said bottom beneath and centrally thereof and transversely thereto, said rocker being adapted to rest on a plane 110

surface and support the tank in an upright position while it rocks thereon.

2. A developing tank having high sides and ends and a long narrow rectangular bottom, said tank being adapted to hold a photographic film on edge, a rocker attached beneath and to said bottom centrally thereof, and across said bottom, said rocker extending beyond the sides of said tank and being adapted to rest on a plane surface and

support said tank in an upright position while it rocks thereon, a larger tank surrounding said developing tank in which it is adapted to be placed and from which it can be removed and in which it can freely rock 15 on said rocker, said tank being laterally spaced from said larger tank by said rocker.

In testimony whereof I affix my signature.

PLINY W. SMITH.
